FISHING LURE RETRIEVER

Denny L. Howerter, 3817 NW. 60th,
Oklahoma City, Okla. 73112

Filed June 12, 1970, Ser. No. 23,446

Term of patent 14 years

Int. Cl. D22—05

U.S. Cl. D22—31

FIG. 1 is a perspective view of the fishing lure retriever from one side and looking slightly down on the retriever.

FIG. 2 is a perspective view of the retriever from the opposite and looking slightly up at the retriever.

FIG. 3 is a top view of the retriever.

I claim:

The ornamental design for a fishing lure retriever, as shown.
